Primary Examiner—Brian N. Vinson*Attorney, Agent, or Firm*—Sughrue, Mion, Zinn, Macpeak & Seas, PLLC**[57] CLAIM**

The ornamental design for an integrated circuit device, as shown.

DESCRIPTION

FIG. 1 is a perspective view of the top, front and left side of an integrated circuit device showing our new design;

FIG. 2 is a top plan view thereof;

FIG. 3 is a bottom plan view thereof;

FIG. 4 is a left side elevational view thereof;

FIG. 5 is a right side elevational view thereof;

FIG. 6 is a front elevational view thereof; and,

FIG. 7 is a rear elevational view thereof.
